Primary Examiner — Robert M. Spear*(74) Attorney, Agent, or Firm* — Nicholas Pfeifer; Smith & Hopen, P.A.(57) **CLAIM**

The ornamental design for a box with an inflatable bladder and inflation valve, as shown and described.

DESCRIPTION

FIG. 1 is a front perspective view of the box with an inflatable bladder and inflation valve;

FIG. 2 is a rear perspective view of the box shown in FIG. 1;

FIG. 3 is a top view of the box shown in FIG. 1;

FIG. 4 is a bottom view of the box shown in FIG. 1;

FIG. 5 is a side view of the box shown in FIG. 1;

FIG. 6 is a front view of the box shown in FIG. 1;

FIG. 7 is a rear view of the box shown in FIG. 1;

FIG. 8 is a top plan view of the box shown in FIG. 1, but in a disassembled configuration; and,

FIG. 9 is a bottom plan view of the box with an inflation valve as shown in FIG. 1, but in a disassembled configuration.

The broken lines in the drawings depict unclaimed environment and form no part of the claim.
